(57) **CLAIM**

The ornamental design for a planter, as shown and described.

DESCRIPTION

FIG. 1 is a front elevation view of a planter;

FIG. 2 is a top plan view thereof;

FIG. 3 is a left side elevation view thereof;

FIG. 4 is a right side elevation view thereof;

FIG. 5 is a rear elevation view thereof;

FIG. 6 is a bottom plan view thereof;

FIG. 7 is a front, top and right side perspective view thereof; and,

FIG. 8 is a front, bottom and right side perspective view thereof.

The evenly spaced broken lines depict portions of the planter that form no part of the claimed design. The dot-dot-dash boundary line in FIGS. 2 and 7 defines the bounds of the claim and forms no part thereof.
